UNITED STATES PATENT OFFICE.

HARRY E. KHOURY, OF NEW BEDFORD, MASSACHUSETTS.

WARP STOP MOTION FOR LOOMS.

Application filed May 5, 1924. Serial No. 711,153.

To all whom it may concern:

Be it known that HARRY E. KHOURY, a citizen of Syria, a protectorate of France, residing at New Bedford, in the county of 5 Bristol and State of Massachusetts, has invented new and useful Improvements in Warp Stop Motions for Looms, of which the following is a specification.

The present invention relates to warp 10 stop motions for looms, and more particularly to that type of stop motions wherein the harness or shed-forming heddles perform the additional function of detector wires, which serve to stop the loom whenever one of the warp threads breaks.

The invention relates to the type of mechanism disclosed in my co-pending application, Serial No. 606,194, filed December 11, 1922, which shows a stop motion comprising 20 a rockable bar mounted in each of the heddle frames and adapted to be rocked as the frames are reciprocated vertically in the loom operation. The mechanism also embodies means upon the loom, which effects rocking of the bar and also serves to maintain a power operated knock-off mechanism inoperative. The bar rocking means is connected with the knock-off mechanism so that upon the locking of the bar against 25 rocking movement when one of the warp threads, breaks, the knock-off mechanism is rendered operative and the loom stopped.

The present invention is an improvement upon the structure disclosed in my co-pending 35 application, in that it discloses a simplified means for rendering the knock-off mechanism operative when one of the rock-ing bars in the heddle frames is locked against rocking movement.

An object of the invention is to provide 40 a warp stop motion of simple construction, which will be positive and unfailing in operation. These and other objects of the invention, such as the provision of a mech-45 anism which may be readily attached to a loom, and which may be cheaply manu-factured, will become apparent as the de-scription proceeds in connection with the preferred embodiment disclosed in the accompanying drawings, wherein:

Figure 1 is a vertical section of a loom taken through the heddle frames and looking toward one side.

Figure 2 is a top plan view of the mech-55 anism shown in Figure 1,

Figure 3 is an enlarged detail view of the knock-off mechanism,

Figure 4 is a vertical section on the line 4-4 of Figure 3, looking in the direction of the arrows,

Figure 5 is an enlarged detail of the knock-off mechanism, showing the relative positions of the parts when the knock-off mechanism is operative, and

Figure 6 is an end view of the mechanism 65 shown in Figure 5, with the parts in the position indicated in that figure.

Referring to the drawings for a more detailed description, 10 indicates a portion of one of the side frame pieces of a loom, in 70 which is mounted a drive shaft 11 carrying fast and loose pulleys 12, a driving belt 13 being shiftable by means of a lever 14 mounted upon a bracket 15. One end of the lever is forked, as at 16, and it is operated 75 by means of a shipper lever 17, which is movable laterally to be seated in a recess 18 in a slotted bracket when the belt is upon the fast pulley for the operation of the mechanism. The loom also includes the 80 usual harness frames 19, 20, which are vertically reciprocated, as will be understood, as by a harness strap 21, passing over sheaves 22. Non-circular rock shafts 23 are mounted in the frames and extend through shed-forming heddles 24, which are provided with loops 24', having narrowed portions 24".

When a warp thread breaks and the heddle drops, the narrowed portions 24" fit over the non-circular rock shafts 23 and lock the lat-85 ter against rocking movement. As will be understood, the heddles are supported by the warp threads as long as the threads are unbroken or not too slack, and it is only upon dropping of one of the heddles that the 90 rock shaft will be locked against movement. It is thought that no detailed description of the operation of the heddles or the loom is necessary, since this much of the mechanism 95 is old and well known in the art, and is disclosed and described in detail in my co-pending application, referred to above.

It will be noted that each rock shaft 23 ex-100 tends beyond the frame and carries an arm 25 adapted to engage an arm or pin 26 upon a rock shaft 27 supported upon the loom frame in bearings 29 formed upon vertical bracket arms 28. The bracket arms extend through eyes 30 in horizontal bracket arms 31, and are held in position by set screws 32. 110

The bracket arms 31 are mounted upon a longitudinally movable rod 33, which has one end extending through a bracket 34 upon the frame and provided with a laterally deflected portion 33' to form a hook adapted to engage the shipper lever 18 when the rod is moved toward the right, as viewed in Figure 2. At its opposite end, the rod 33 has threaded thereon a loop 35, which is pivotally connected to a lever 36 fulcrumed at 37 upon a bracket plate 38, suitably supported upon the frame. The rod 33, together with the lever 36, constitute a portion of the knock-off mechanism, which is power actuated from the drive shaft 11. The lever 36, which constitutes a normally stationary member of the knock-off mechanism carries a pawl or finger 39, having a depending shank portion 39', and a shoulder 40. The finger is pivotally supported upon the lever by means of a pin 41, extending through an opening 42 in an ear 43 projecting laterally from the lever. The finger is free to swing about its pivot pin 41 and has its shoulder normally depressed, as indicated in Figure 3, by means of a detent 44, upon the end of the rock shaft 27. The detent has a shank portion 45 formed with an eye 46 into which fits the shaft 27, a set screw 47 serving to maintain the detent in fixed position upon the shaft. The detent is held in engagement with the finger 39 by means of a coil spring 48, one end of which projects into a collar 49 upon the rock shaft, the other end of the same engaging the bracket arm 29. In this manner the spring is suitably tensioned to hold the detent 44 above the shoulder 40 of the finger and retain the latter in its normal position indicated in Figure 1. The finger 39 is also a portion of the knock-off mechanism and is adapted to be engaged by a lug 50 carried by a continuously moving lever 51 pivoted at 52 upon the plate 38. The lever is actuated through a pitman 53, which extends through a guide bracket 54, and at its lower end is pivotally connected, as at 55, to the end of a cam lever 56 pivoted upon the frame 56' and carrying a cam block 57 engaging a heart-shaped cam 58 upon a counter shaft 59 suitably driven from the shaft 11 by gearing indicated in dotted lines. The cam block 57 is urged toward the cam by means of a coil spring 60 surrounding the pitman, and, as will be understood, rotation of shaft 59 results in reciprocation of pitman 53 and operation of lever 51. As the lever 51 is moved about its fulcrum 52, the lug 50 clears the end of the finger 39, and thus the knock-off mechanism is inoperative. The rock shaft 27 and detent 44 are maintained in the position shown in Figures 1, 3 and 4 while no warp threads are broken. Under these conditions the heddle frames move up and down, and engagement of the arms 25 with arms or pins

26 upon the rock shaft 27 as the heddle frames descend, serve to rock the bars 23, the arms moving upwardly as they engage the pins 26. As the heddle frames ascend, the rock shafts may be returned to lower 70 the arms 25, either by gravity or suitable spring means, such as is disclosed in my co-pending application. However, should one of the warp threads break, its heddle drops and locks the bar 23 against rocking movement. Upon the next descent of the heddle frame, engagement of the arm 25 upon the rock bar with the pin or arm 26 upon the rock shaft 27, will rock the shaft 27 in opposition to the spring 48 and throw the detent 44 to the position indicated in Figure 6. Movement of the detent 44 from the position shown in Figure 4 to its position indicated in Figure 6 is limited by means of a stop collar 65, mounted upon the rock shaft 27 having a finger portion 65' projecting longitudinally of the shaft and adapted upon rocking movement of the shaft 27 to engage a bracket arm 28. This movement of the detent will at once release the finger 39 and permit the weight of the shank 39' of the same to swing the shoulder 40 of the finger into the path of the lug 50. Upon the next upward movement of the lever 51 of the knock-off mechanism through pitman 53, the lug 50 will engage the shoulder 40 of finger 39 and move the lever 36 to the right, as viewed in Figures 1 and 3. The engagement of the lug and finger is shown in Figure 5, and as the lever 36 is moved to the right, movement in the same direction is imparted to rod 33, to which the lever is connected, thereby causing engagement of the end of the rod 33' with the shipper lever 17 and permitting the actuating spring 17' to 105 shift the belt 13. A coil spring 33'' serves to return the lever 36 and rod 33 to its normal position after the shipper lever has been thrown, and the stop collar 34', by engaging the bracket 34, limits the movement of the 110 rod 33 under the influence of the spring 33''. It should be understood that numerous modifications may be made in the embodiment of the invention illustrated in the accompanying drawings without departing 115 from the gist of the invention. As will be observed, the knock-off mechanism has power actuated from cam 58 upon shaft 59 and comprises the continuously moving lever 51, carrying the lug 50, which, when any one of the warp threads breaks, serves to actuate the shipper lever. The lug 50, however, is normally disconnected from the remaining portion of the knock-off mechanism, namely, the lever 36 and rod 33, due to the 120 fact that the normally stationary interposed finger 39 is held in an inoperative position by means of the detent 44. Once the detent is released, however, due to the locking of one of the rock shafts 23 in one of the hed- 125 130

idle frames, the finger swings of its own weight to the operative position shown in Figure 5, and the shoulder 40 thereon is thus moved into the path of the lug 50. If 5 desired, the end 44' of the detent may be bevelled (Fig. 6) so that as the detent is returned to its operative position (Fig. 4) under the influence of spring 48, after it has once been moved to release finger 39, the de- 10 tent will automatically depress the finger 39 and thus return the same to an inoperative position. The parts of the knock-off mechanism are thereby automatically reset, due to the provision of spring 33', which 15 returns the lever 36 and rod 33 and the spring 48, which returns the detent and finger 39. With the parts thus reset, after the operator has connected the ends of the broken warp thread, the shipper lever 18 20 may be manually swung to return the belt 13 to the fast pulley and thereby resume the operation of the loom.

I claim:

1. In a warp stop motion for looms, the 25 combination with the heddle frame and shed-forming heddles, of a rockable bar associated with the heddles and mounted in the heddle frame, the heddles being formed to lock the bar against rocking movement 30 when one of the warp threads breaks, normally stationary means on the loom adapted to rock the bar as the heddle frame moves, and power actuated means to stop the loom, said stop means being positively maintained 35 inoperative to stop the loom through connections with said bar rocking means as long as the bar is free to rock.

2. In a warp stop motion for looms, the 40 combination with the heddle frame and shed-forming heddles, of a rockable bar associated with the heddles and mounted in the heddle frame, the heddles being formed to lock the bar against rocking movement when one of the warp threads breaks, normally stationary movable means on the loom adapted to rock the bar as the heddle frame moves, and power actuated means to stop the loom, said stop means being positively maintained inoperative to stop the 45 loom through connections with said bar rocking means as long as the bar is free to rock.

3. In a warp stop motion for looms, the 55 combination with the heddle frame and shed-forming heddles, of a rockable bar associated with the heddles and mounted in the heddle frame, the heddles being formed to lock the bar against rocking movement when one of the warp threads breaks, normally stationary movable means on the loom adapted to engage and rock the bar as the heddle frame moves, and power actuated means to stop the loom, said stop means being positively maintained inopera- 60 tive to stop the loom through connections 65

with said bar rocking means as long as the bar is free to rock.

4. In a warp stop motion for looms, the 70 combination with a heddle frame and shed-forming heddles, of a rockable bar associated with the heddles and mounted in the heddle frame, the heddles being formed to lock the bar against rocking movement when one of the warp threads breaks, normally 75 stationary movable means on the loom adapted to rock said bar as the heddle frame moves, power actuated means to stop the loom, said stop means including a continuously moving member, a relatively stationary member, a connection between said members adapted to be maintained inoperative, and means actuatable through said bar rocking means to render said connection operative, said bar serving when locked to actuate 80 said last mentioned means. 85

5. In a warp stop motion for looms, the 90 combination with the heddle frame and shed-forming heddles, of a rockable bar associated with the heddles and mounted in the heddle frame, the heddles being formed to lock the bar against rocking movement when one of the warp threads breaks, normally stationary movable means on the loom adapted to rock said bar as the heddle frame moves, power actuated means to stop the 95 loom, said stop means including a continuously moving member, a relatively stationary member, a connection between said members adapted to be held in inoperative position, and means operative through said bar rocking means to release said connection, 100 said bar serving when locked to operate said last mentioned means.

6. In a warp stop motion for looms, the 105 combination with the heddle frame and shed-forming heddles, of a rockable bar associated with the heddles and mounted in the heddle frame, the heddles being formed to lock the bar against rocking movement when one of the warp threads breaks, means 110 on the loom adapted to rock the bar as the heddle frame moves, power actuated means to stop the loom including a continuously moving member, a stationary member connected with the loom shipper lever, a normally stationary finger connected with said stationary member and adapted to be engaged by said continuously moving member, means for normally maintaining said finger out of engagement with said moving member, said last mentioned means being operable through said bar rocking means to permit the finger to be engaged by said moving member when said bar is locked. 115

7. In a warp stop motion for looms, the 120 combination with the heddle frame and shed-forming heddles, of a rockable bar associated with the heddles and mounted in the heddle frame, the heddles being formed to lock the bar against rocking movement 125 130

when one of the warp threads breaks, normally stationary movable means on the loom adapted to rock the bar as the heddle frame moves, power actuated means to stop the loom including a continuously moving member, a stationary member connected with the loom shipper lever, a normally stationary finger connected with said stationary member and adapted to be engaged by said continuously moving member, and means for normally maintaining said finger out of engagement with said moving member, said last mentioned means being operable through said bar rocking means to permit the finger to be engaged by said moving member when said bar is locked.

8. In a warp stop motion for looms, the combination with the heddle frame and shed-forming heddles, of a rockable bar associated with the heddles and mounted in the heddle frame, the heddles being formed to lock the bar against rocking movement when one of the warp threads breaks, a power actuated loom stop means on the loom including a continuously moving member, a stationary member connected with the loom shipper lever, a normally stationary finger connected to said stationary member and adapted to be engaged by said moving member to stop the loom, a rock shaft having a detent normally engaging said finger to hold the same out of the path of said moving member, and means on said rock shaft for rocking said heddle frame bar, the bar serving when locked to rock said shaft and thereby to permit operation of said stop means.

9. In a warp stop motion for looms, the combination with the heddle frame and shed-forming heddles, of a rockable bar associated with the heddles and mounted in the heddle frame, the heddles being formed to lock the bar against rocking movement when one of the warp threads breaks, normally stationary means on the loom adapted to rock the bar as the heddle frame moves, power actuated means to stop the loom, said means being normally inoperative to stop the loom, means for rendering said stop means operative when the bar is locked against rocking movement, and means for automatically rendering the stop means inoperative after the loom has once been stopped.

10. In a warp stop motion for looms, the combination with the heddle frame and shed-forming heddles, of a rockable bar associated with the heddles and mounted in the heddle frame, the heddles being formed to lock the bar against rocking movement when one of the warp threads breaks, normally stationary movable means on the loom adapted to rock the bar as the heddle frame moves, power actuated means to stop the loom, said means being normally inoperative to stop the loom, means actuatable

through said bar rocking means for rendering said stop means operative when the bar is locked against rocking movement, and means for automatically rendering the stop means again inoperative after the loom has been stopped.

11. In a warp stop motion for looms, the combination with the heddle frame and shed-forming heddles, of a rockable bar associated with the heddles and mounted in the heddle frame, the heddles being formed to lock the bar against rocking movement when one of the warp threads breaks, normally stationary movable means on the loom adapted to rock said bar as the heddle frame moves, power actuated means to stop the loom, said stop means including a continuously moving member, a relatively stationary member, a connection between said members adapted to be maintained inoperative, means actuatable through said bar rocking means to render said connection operative, said bar serving when locked to actuate said last mentioned means, and means for automatically returning said connection to inoperative position when the stop means has once effected stopping of the loom.

12. In a warp stop motion for looms, the combination with the heddle frame and shed-forming heddles, of a rockable bar associated with the heddles and mounted in the heddle frame, the heddles being formed to lock the bar against rocking movement when one of the warp threads breaks, normally stationary movable means on the loom adapted to rock said bar as the heddle frame moves, power actuated means to stop the loom, said stop means including a continuously moving member, a relatively stationary member, a connection between said members adapted to be held in inoperative position, means operative through said bar rocking means to release said connection, said bar serving when locked to operate said last mentioned means, and means for automatically returning said connection to inoperative position after the stop means has once effected stopping of the loom.

13. In a warp stop motion for looms, the combination with the heddle frame and shed-forming heddles, of a rockable bar associated with the heddles and mounted in the heddle frame, the heddles being formed to lock the bar against rocking movement when one of the warp threads breaks, a power actuated loom stop means in the loom including a continuously moving member, a stationary member connected with the loom shipper lever, a normally stationary finger connected to said stationary member and adapted to be engaged by said moving member to stop the loom, and a rock shaft having detent normally engaging said finger to hold the same out of the path of said moving member, means on said rock shaft for rocking said

5 heddle frame bar, the bar serving when locked to rock said shaft and thereby to permit operation of said stop means, and means for automatically effecting the re-engagement of said detent and finger after the stop means has once effected stopping of the loom.

10 14. In a warp stop motion for looms, the combination with the heddle frame and shedding heddles, of a rockable bar associated with the heddles and mounted in the heddle frame, the heddles being formed to lock the bar against rocking movement when one of the warp threads breaks, normally

stationary movable means on the loom 15 adapted to rock the bar as the heddle frame moves, power actuated means to stop the loom, said means being normally inoperative to stop the loom, means for rendering said stop means operative when the bar is 20 locked against rocking movement, and means for automatically rendering the stop means inoperative after the loom has once been stopped.

In testimony whereof I have hereunto set 25 my hand.

HARRY E. KHOURY.
